UNITED STATES PATENT OFFICE.

FREDERICK C. SCHOEN, OF NEW YORK, N. Y., ASSIGNOR TO LIDGERWOOD MANUFACTURING COMPANY, A CORPORATION OF NEW YORK.

HYDRAULIC TELEMOtor.

966,479.

Specification of Letters Patent.

Patented Aug. 9, 1910.

Application filed July 30, 1909. Serial No. 510,384.

To all whom it may concern:

Be it known that I, FREDERICK C. SCHOEN, a citizen of the United States, and a resident of the city of New York, borough of Brooklyn, county of Kings, and State of New York, have invented certain new and useful Improvements in Hydraulic Telemotors, of which the following is a specification.

My invention relates to hydraulic telemotors of well-known form wherein the operating valve of a ship's steering engine is controlled through its connection with mechanism comprising hydraulic cylinders and pistons operated by the turning of the wheel in the ship's pilot house. The operation of such a system is liable to be deranged or rendered faulty through leakage of the hydraulic cylinders, and it is the purpose of my invention to provide mechanism of novel form whereby the results of such leakage may be overcome and the efficient operation of the mechanism restored.

For the purpose of illustrating my invention I have shown the preferred form of my device in the drawings herewith and will hereafter describe the same as used in connection with a hydraulic telemotor of well-known form, but I do not desire thereby to limit my device to such use, my invention consisting in the design, arrangement, construction and operation of parts as set forth in and falling within the scope of the claims hereto appended.

In the drawings herewith like characters of reference denote like parts in all the figures thereof.

Figure 1 represents a view in side elevation of a portion of the steering apparatus comprising the steering wheel and column and one hydraulic cylinder. Fig. 2 represents a detail end view in section of a portion of the mechanism shown in Fig. 1. Fig. 3 represents a plan view partially in section of another portion of the steering apparatus comprising the second hydraulic cylinder, its connection to the engine valve, and my novel equalizing device. Fig. 4 represents a view in side elevation of the second cylinder and my novel equalizing device. Fig. 5 represents an end view in elevation of a portion of my novel equalizing device.

Turning to a detail description of the form of hydraulic telemotor shown in the

drawings in connection with Figs. 1, 2 and 3, reference numeral 1 indicates the steering column located in the pilot house of the ship. The steering wheel 2 is connected through pinions 3 with shaft 4 having at its lower end the bevel pinion 5. Pinion 5 meshes with a bevel pinion 6 mounted in the bearing 7. The pinion 6 is provided with a screw-threaded bore passing through its center lengthwise of the pinion, and through this bore passes a screw-threaded rod 8 mounted in bearing 9. In order that the rod 8 will not turn upon movement of pinion 6, a feather 10 is provided in the bearing 9 entering a groove in the rod 8. Connected to the rod 8 is a piston rod 11 entering and passing through the cylinder 13, being provided with a piston head 12 adapted normally to be positioned centrally of the cylinder, as shown in Fig. 1. At the center of the cylinder in the walls thereof are provided by-passes 14 and 15 so positioned that when the piston head 12 is in its normal central position the fluid contained in the cylinder will be permitted to flow through the by-passes from one end of the cylinder to the other. A pipe connection 16 is provided whereby connection may be had with a tank, not shown, used for filling the cylinder. From the cylinder 13 pipes 17 and 17' extending from opposite ends lead to opposite ends of a second hydraulic cylinder 18, which in turn is provided with a piston head 19 mounted upon the rod 20 and normally adapted to be positioned centrally of the cylinder. Through links 21 and 23 and the pivoted bell crank lever 22 the piston rod 20 is connected with a sleeve 24 passing through a bearing 25. The interior surface of the sleeve 24 is screw-threaded and a screw-threaded rod 26 passes into the sleeve 24. A collar 27 is mounted on the rod 26, connection being had between the collar 27 and the operating valve of the steering engine. As this engine valve construction forms no part of this invention, I have not deemed it necessary to illustrate the same as any one skilled in the art can understand the application of the invention without detailed description or illustration thereof. The rod 26 is extended in shaft 28 provided with pinion 29 adapted to mesh with the gear 30 on the drum of the steering engine.

It will be understood that the engaging faces of the gears 29 and 30 are so proportioned that they will always remain in mesh during all positions of the shaft 28 during the operation of the mechanism.

The operation of the hydraulic telemotor in brief is as follows. Upon the turning of the steering wheel 2 the pinion 6 will be turned and the rod 8 will be moved longitudinally in accordance with the direction in which pinion 6 is turned, thereby moving the piston head 12 longitudinally within the cylinder 13. For example, should the piston head 12 move toward the end of the cylinder connected with pipe 17', the liquid in the cylinder will be forced through pipe 17' into one end of the cylinder 18, thereby forcing the piston head 19 in that cylinder in the opposite direction from the movement of piston head 12 in cylinder 13. In this instance, the piston head 19 will move to the left in cylinder 18 and through the connections of rod 20 with sleeve 24 said sleeve 24 will be moved upward through its bearing 25, drawing up rod 26, and, through the connection of collar 27 with the operating valve of the engine, opening said valve to a desired extent. Upon the opening of the valve, the steering engine will be operated and the drum of the steering engine revolved. The revolution of the steering engine drum through connection of its gear 30 with the pinion 29 operates to revolve the rod 28-26, the portion 26 thereupon moving out of the sleeve 24 by reason of its screw-thread connection with the inner surface thereof and the collar 27 resuming its normal position. In this manner it will be seen that any turning of the wheel in the pilot house results in the operation of the engine valve and the operation of the steering engine to any desired extent. The movement of the sleeve 24 in either direction is limited by the collars 31 and 32, which contact with bearing 25, such limited positions corresponding to the movement of the rudder either hard to port or hard to starboard.

The operation of the steering engine has not been described in full since such an engine is well-known in the art, as shown, for example, in Patent No. 486,007 issued November 8, 1892.

It will readily be seen that the position of the piston head 19 in cylinder 18 should, at all times, correspond to the position of piston head 12 in cylinder 13 with the difference, however, that said piston heads move in opposite directions when operated. However, through leakage of the liquid contained in the cylinders 13 and 18, it sometimes occurs that the movement of piston head 19 does not always follow upon the movement of the piston head 12. Since the piston head 12 is mechanically connected to the steering wheel, its position in the cylinder 13 can be

positively controlled, but, when leakage has occurred, the position of the piston head 19 in cylinder 18 cannot be controlled since control of said piston head is had only through the liquid contained in the cylinders and their connecting pipes.

On the top of the steering column 1 is located a pointer 33, the movement of which pointer corresponds with the movement of the steering wheel and shows the man at the wheel exactly the position of the rudder when the hydraulic system is in perfect working order. Should the system, however, be faulty in its operation through leakage, the position of the pointer 33 upon the steering column will not correspond with the position of the rudder since the piston head 19 will not have been operated, or will have operated only to a limited extent, upon movement of the piston head 12 in cylinder 13 and the engine valve will, therefore, not have been operated to bring the rudder to the desired position. In order that the man at the wheel may be informed of such faulty operation of the telemotor it is customary to have in the pilot house a separate indicating device directly connected with the rudder which at all times shows the exact position of the rudder. Through comparison of this separate indicating device with the pointer 33 the man at the wheel may readily tell when the rudder is in a position other than that indicated by pointer 33. Having observed such faulty operation of the telemotor and the rudder not being in the desired position, it is necessary to correct the fault in the operation of the telemotor and bring the rudder to the desired position, and it is the object of my invention, as has been stated, to provide a novel means whereby the man at the wheel may achieve this purpose.

Turning to Figs. 4 and 5, it will be seen that the piston rod 20, at its end opposite to that of its connection with link 21, is connected with a rack 34 movable lengthwise in the bearing in the stand 35. Mounted in bearings in the stand 35 is a shaft 36 provided with a gear pinion 37 meshing with the rack 34. Upon one of the outer ends of shaft 36 is mounted a toothed sprocket wheel 38 over which passes a chain 39 provided at each end with a rod 40 passing downward through apertures in weights 41. The aperture through which each rod 40 passes is of such size that the rod 40 may be lowered without disturbing the weights 41 which rest upon a shelf 42, but, should the rod 40 be raised, a plate 43 at the bottom of the rod will engage with the weights 41 and the weights will be raised with the rod, being guided in their movement upward by the guides 44. The weights 41 and the chain 39 and rods 40 are so arranged that when the piston head 19 is centrally posi-

tioned within the cylinder 18 both sets of weights 41 will be resting upon the shelf 42. Therefore, upon the movement of the piston head 19 lengthwise in the cylinder 18 in either direction the rack 34 will also be moved longitudinally. The gear 37 and the sprocket wheel 38 will be revolved and one of the sets of weights 41 will be elevated from the shelf 42 to a degree corresponding with the movement of the piston head 19. If the telemotor is in perfect operating condition—in other words, if the cylinders and their connecting pipes are completely filled with liquid, generally water, and there has been no leakage—the weight of the elevated weights 41 will not have any power to return the piston head 19 to its central position in the cylinder against the action of the liquid contained in the cylinder, but, on the other hand, should leakage have occurred, the cylinders and their connecting pipes will not be filled to their full extent with liquid and the weights 41, which have been elevated, will then have power to move the piston head 19 back to its central position in the cylinder 18, at which time the weights will again come to rest on the shelf 42. This operation takes place in the following manner. Upon the man at the wheel observing that the real position of the rudder does not correspond with the position of the pointer 33, he operates the wheel 2 to bring the pointer 33 to a position corresponding with the dead center position of the rudder. By so doing, the piston head 12 is moved to a central position in the cylinder 13 and the water in such cylinder is free to move from one end to the other around the piston head. Thereupon, there being a free circulation of the water in cylinder 13, the set of weights 41, which have been elevated, will fall by reason of gravity, revolving the sprocket wheel 38 and moving the rack 34 longitudinally, thereby resulting, through connection of the rack with the rod 20, a movement of the piston head 19 back to a central position in the cylinder 18. Such a movement of the piston head 19 to its normal central position results in the operation of the engine valve to bring the rudder to a central position and the system is thus restored to perfect working order, the rudder being dead center corresponding to the pointer 33, and each of the piston heads being centrally positioned in their cylinders. The liquid which has been lost by leakage is restored through the inlet 16 from the supply tank, and operation of the steering apparatus may be resumed. This restoring of the system to perfect working order occupies but a brief space of time.

From the foregoing description it will be seen that I have provided a device simple in

construction, and operation, whereby any fault or error in the operation of a hydraulic telemotor may be readily corrected and the telemotor restored to its full efficiency without loss of time or labor.

Having thus described my invention, what I claim and desire to secure by Letters Patent of the United States is:—

1. The combination with a telemotor comprising a cylinder, a piston and a piston head therein, said piston head being normally positioned centrally of the cylinder, and means for operating the piston and piston head, of means adapted to return the piston head to its central position after the operation thereof, said last-mentioned means comprising a weight adapted to be elevated upon the operation of the piston head.

2. The combination with a telemotor comprising a cylinder, a piston and a piston head therein, said piston head being normally positioned centrally of the cylinder, and means for operating the piston and piston head, of means adapted to return the piston head to its central position after the operation thereof, said last-mentioned means comprising a plurality of weights one of which is adapted to be elevated upon the operation of the piston head.

3. The combination with a telemotor comprising a cylinder, a piston and a piston head therein, said piston head being normally positioned centrally of the cylinder, and means for operating the piston and piston head, of means adapted to return the piston head to its central position after the operation thereof, said last-mentioned means comprising a sprocket wheel, a chain passing over said wheel, and a weight attached to the chain, said wheel being adapted to operate to elevate the weight upon the operation of the piston head.

4. The combination with a telemotor comprising a cylinder, a piston and a piston head therein, said piston head being normally positioned centrally of the cylinder, and means for operating the piston and piston head, of means adapted to return the piston head to its central position after the operation thereof, said last-mentioned means comprising a rack connected to the piston rod, a pinion engaging with said rack, a weight and connections between the pinion and the weight adapted to operate to elevate the weight upon the operation of the pinion.

In testimony whereof I have hereunto signed my name in the presence of two subscribing witnesses.

FREDERICK C. SCHOEN.
